INKWELL

Gustav J. Sengbusch, Milwaukee, Wis.

Application April 17, 1933, Serial No. 666,414

12 Claims. (Cl. 120—58)

This invention relates to an improved inkwell construction, and has particular reference to the construction of inkwells designed for mounting in school desks and for like purposes. This application is, in part, a continuation of my co-pending application, Serial No. 542,707, filed September 27, 1932.

The main objects of the invention are, to provide a practically non-breakable inkwell; to provide an inkwell having a lid permanently attached thereto, and which, when in closed position, will effectively prevent evaporation of ink therefrom; to provide an inkwell structure in which ink evaporation is reduced to a minimum, even when the lid is open, and in which the entrance of dust and other foreign matter into the inkwell is reduced to a minimum when the lid is opened; to provide an inkwell in which the lid will always be easily openable, i. e. will not stick in closed position; to provide a guard which will project the inkwell and which will also serve to yieldingly hold the inkwell in predetermined position; and, in general, it is the object of the invention to provide an improved inkwell construction.

The advantages of the invention will be understood by reference to the following specification and the accompanying drawing, in which I have illustrated a preferred embodiment of my improved inkwell construction and certain modifications thereof.

In the drawing:

Fig. 1 is a plan;

Fig. 2 is a section on the line 2—2 of Fig. 1;

Fig. 3 is a perspective illustrating the guard in place in a desk and the inkwell removed from the desk opening and guard;

Fig. 4 is a perspective of a modified arrangement;

Fig. 5 is a section corresponding to a portion of Fig. 2 but of the structure illustrated in Fig. 4; and

Fig. 6 is a section similar to Fig. 5, but showing a still further modification.

Referring now to the drawing, my improved inkwell embodies a one-piece receptacle, in this instance, shown as of substantially cylindrical formation, the receptacle including integrally molded side and end wall portions 5, 6 and 7. The receptacle is preferably molded of a suitable hard rubber composition which satisfactorily resists corrosion due to acids contained in ink.

When my improved inkwell construction is to be used on school desks, it is preferably provided

with a reduced-diameter lower end portion, as indicated at 8, which may be fitted into an opening provided in the top 9 of the desk in accordance with more or less customary practice.

The upper end wall 6 is provided with an opening 10 which affords access to the interior of the wall so that a pen may be dipped in the ink contained therein and so that ink may be supplied to the inkwell. The opening 10 is preferably of small area relative to the area of the interior of the receptacle, so that evaporation of ink therefrom is greatly retarded and so that the settlement of dust or insertion of paper scraps and other foreign matter into the inkwell is obstructed.

For closing the inkwell, a lid 11 is provided. In the construction shown in Figs. 1, 2 and 3, the lid is hinged on the top of the inkwell by having a lip 12, which extends from the rear edge of the lid, bent or rolled around a pintle 13. The pintle 13 may be secured to the inkwell in various ways, but in the preferred form of construction, it is secured by having its opposite end portions which project beyond the sides of the rolled lip 12, embedded in the top wall of the inkwell. As shown, the top wall is provided with upstanding portions 14 in which the hinged pintle end portions are embedded.

As clearly shown in Figs. 2 and 3, the top of the inkwell is recessed, in fact double recessed, so as to provide a recess 15 of a depth substantially the same as the thickness of the lid plate 11 and a recess 16 which provides an air space between the bottom of the lid plate and the top surface of the recessed top wall portion. The lid is thus positioned substantially flush with the surrounding top surface of the top wall 6. The space between the lid plate and the recessed top wall portion in which the opening 10 is located, serves to prevent sweating, i. e. accumulation of ink moisture on the bottom of the lid plate, thereby preventing ink from gradually accumulating and acting as an adhesive to ultimately stick the lid in closed position.

In the form shown in Figs. 1, 2 and 3, the top of the inkwell is provided with a peripheral flange 17 which is adapted to overlie the edge portion of the desk around the opening therein to support the inkwell and to provide a nicely finished appearance. The supporting function may be only secondary in view of other supporting means which will presently be described.

As shown in Figs. 2 and 3, the inkwell is mounted in a desk opening in connection with a guard element 18. The guard element 18 embodies a

bottom or end wall 19 having a central aperture 20 and a plurality of fingers 21 extending upwardly from the periphery of the end wall in circumferentially spaced relation. At their upper ends, the fingers are bent laterally outwardly to provide ears 22 and these ears are notched so as to form teeth 23.

The guard is secured in position in an opening in the desk top by having the toothed ear portions of its fingers driven into the material of the top as an incident to spreading of the fingers which are initially bent inwardly so as to permit their upper ends to freely enter the opening in the desk. If desired, the teeth 23 may be slightly sharpened to facilitate entrance thereof into the desk top. The guard is preferably made of metal which is slightly resilient so that the fingers, after being driven the full distance into the desk, will spring back slightly. In Fig. 3, the fingers are shown in their normal returned position leaving small spaces as indicated at 24 into which the teeth may be forced when the inkwell is inserted into the guard. The diameter of the lower portion of the inkwell which enters the guard is such that it is slightly greater than the normal diameter between the fingers 21 when permitted to spring inwardly as shown in Fig. 3. It will thus be evident that the fingers 21 will resiliently or yieldingly grip the lower portion of the inkwell.

To prevent rotation of the inkwell, it is provided with lugs such as 25 on the downwardly facing shoulder 26, such lugs being adapted to fit between adjacent ears 22 of the guard (see Fig. 2). The bottoms of the ears 25 may rest on a ledge 27 formed in the desk opening to thereby support the inkwell independently of the upper flange 17 or, if no such ledge 27 is available in the desk, the shoulder 26 of the inkwell may rest directly on the tops of the finger ears 22. Of course, it will be understood that the guard should be so positioned that the tops of the fingers are in proper spaced relation to the surface of the desk so that the shoulder 26 and ear 17 may both engage their respective supporting surfaces. It will also be understood that in cases where there is no ledge such as 27 available in the desk, the teeth 23 may be lengthened slightly to penetrate the desk an amount which will afford adequate support for the guard and the inkwell.

In the form of construction shown in Figs. 4 and 5, the lid structure includes a pair of metallic plates 28 and 29, the plate 28 being a lid plate and the plate 29 being a mounting plate. As clearly shown, the lid plate 28 is hingedly connected to the mounting plate 29 through the agency of a pintle 30 which is embraced by suitably rolled ears formed integrally with the respective plates. The mounting plate 29 is provided with beveled edges as indicated at 31, and it is embedded in the top wall of the inkwell so that portions of the top wall overlie the beveled edges of the plate to firmly secure the mounting plate to the top wall. The top surface of the lid plate 28 and mounting plate 29 is thus substantially flush with the surrounding top surface 32 and the two plate elements together constitute an insert which may be concentric with the inkwell and which may be polished to present a pleasing appearance and to present a color which contrasts with the color of the body of the inkwell. As shown in Fig. 5, the lid is recessed only to receive the thickness of the lid plate 28. If desired a second recess may be provided in this

form to provide the air space arrangement described in connection with Fig. 2.

Another manner of mounting the lid plate in the inkwell is illustrated in Fig. 6. In this form, the lid plate 28 is hingedly connected to the mounting plate 29 through a hinged connection 33 which is offset downwardly and embedded in the top wall of the inkwell so as to provide an entirely flat surface on the inkwell top. In this form of construction, the lid may be opened to an extent of 90 degrees as indicated in dotted lines, whereas in the forms illustrated in Figs. 1 to 5 inclusive, the lid may be swung back through an arc of approximately 180 degrees, as also indicated in dotted lines in Fig. 5 and in full lines in Fig. 3.

In all forms, the top surface of the inkwell may be provided with a recess 34 adjacent the edge of the lid plate to facilitate the insertion of a thumb or finger-nail under the edge of the lid to open same.

In the form of construction illustrated in Figs. 4 to 6 inclusive, the inkwell is not provided with a top flange. In this form of construction, the inkwell is designed to be positioned in a desk with its top surface substantially flush with the desk surface. This form of construction may be mounted in the desk either with or without a guard such as 18, it being merely necessary to provide some form of shoulder in the desk opening on which the shoulder 35 of the inkwell may rest. In the event that lugs such as 25 are also provided on the shoulder 35 so as to adapt the inkwell to use in connection with a guard 18, such lugs will of course, rest on whatever shoulder is provided in the desk.

The described inkwell construction is of itself very durable and when protected by a guard such as 18, is seldom if ever, subjected to any hard forces which might tend to break or damage conventional forms of inkwells. It is also neat and attractive in appearance and capable of being produced at comparatively low cost.

I am aware that changes may be made in the described construction without departing from the spirit of the invention, the scope of which should be determined by reference to the following claims, the same being construed as broadly as possible consistent with the state of the art.

I claim as my invention:

1. An inkwell of the class described, comprising a receptacle of one-piece construction and including integrally formed side and end walls, the upper end wall being provided with an opening of small area relative to the area of the interior of the receptacle, and a metallic lid including a pair of plate parts hinged together, one of said plate parts being embedded and thereby fixedly anchored in the upper end wall of the receptacle and having its top surface substantially flush with the top surface of said upper end wall, the latter being recessed to receive the other plate part in substantially co-planar relation to the embedded part and with its top surface substantially flush with the top surface of said upper end wall, said last-mentioned lid part being thereby hingedly mounted on the upper end of the receptacle in position to close said opening.

2. An inkwell of the class described, comprising a receptacle of one-piece construction and including integrally formed side and end walls, the upper end wall being provided with an opening of small area relative to the area of the interior of the receptacle, and a metallic lid including a pair of plate parts hinged together, one of

- said plate parts having beveled edges and being embedded and thereby fixedly anchored in the upper end wall of the receptacle and having its top surface substantially flush with the top surface of said upper end wall, the latter being recessed to receive the other plate part in substantially co-planar relation to the embedded part and with its top surface substantially flush with the top surfaces of said upper end wall, said last-
5 mentioned lid part being thereby hingedly mounted on the upper end of the receptacle in position to close said opening, and said top wall being provided with a recess adjacent a portion of the edge of said last-mentioned lid part to facilitate opening thereof. 80
- 10 3. An inkwell of the class described, comprising a one-piece molded receptacle having integrally formed side and end walls, the upper end wall being provided with an opening affording access to the interior of the receptacle, a lid for closing said opening, and a plate embedded in the receptacle and co-planar with said lid for hingedly mounting said lid on the receptacle. 85
- 15 4. An inkwell as described in claim 3 wherein said lid and plate are substantially flush with the outer surface of the top end wall. 90
- 20 5. An inkwell of the class described, comprising a one-piece molded receptacle having integrally formed side and end walls, the upper end wall being provided with an opening affording access to the interior of the receptacle, a lid for closing said opening, and a plate hinged to said lid, said plate having a beveled edge molded into the upper end wall of said receptacle whereby an integral portion of said receptacle overhangs said beveled edge so as to lock it in place on the outside of said wall, and said lid being rotatable from a closed position substantially co-planar with said plate through substantially 180 degrees. 95
- 25 6. An inkwell as defined in claim 5, wherein the side wall of said receptacle is substantially cylindrical and said plate and lid are both substantially semi-circular. 100
- 30 7. An inkwell of the class described comprising a receptacle having top, bottom and side walls, the top wall having a shallow recess therein and an opening of smaller area than said recess, said opening extending through said recessed wall portion for affording access to the interior of the receptacle, and a lid plate seated in said recess and having its top surface substantially flush with the adjacent top surface of the receptacle, and means for hingedly mounting said lid on the receptacle. 105
- 35 8. An inkwell of the class described comprising a receptacle having top, bottom and side walls, the top wall having a recess therein and an opening of smaller area than said recess, said opening extending through said recessed wall portion for affording access to the interior of the receptacle, and a lid plate seated in said recess and having its top surface substantially flush with the adjacent top surface of the receptacle, said lid plate being of less thickness than the depth of said recess so as to provide an air space between the lid plate and recessed top wall portion, and means for hingedly mounting said lid on the receptacle. 110
- 40 9. An inkwell of the class described comprising a receptacle having top, bottom and side walls, the top wall having a recess therein and an opening of smaller area than said recess, said opening extending through said recessed wall portion for affording access to the interior of the receptacle, a lid plate hingedly mounted on the inkwell for closing said opening, and means for supporting said lid in closed position in said top recess but in spaced relation to the recessed top surface. 115
- 45 10. An inkwell of the class described comprising a receptacle having top, bottom and side walls, the top wall having a recess therein and an opening of smaller area than said recess, said opening extending through said recessed wall portion for affording access to the interior of the receptacle, a lid plate hingedly mounted on the inkwell for closing said opening, and a peripheral shoulder in said recess for engaging a marginal portion of said lid to support the lid in closed position in said top recess but in spaced relation to the recessed top surface. 120
- 50 11. In combination, an inkwell adapted to be mounted in an opening in a desk, and a guard mounted in the opening, comprising an end member and a series of fingers extending upwardly from the end member into said opening for yieldingly gripping a portion of the inkwell, and ears on the free ends of said fingers for biting into the desk intermediate its thickness to secure the guard to the desk. 125
- 55 12. In combination, an inkwell adapted to be mounted in an opening in a desk, and a guard mounted in the opening, comprising an end member and a series of fingers extending upwardly from the end member into said opening, and ears carried by some of said fingers for biting into the desk intermediate its thickness to secure the guard to the desk. 130
